UNITED STATES PATENT OFFICE

ABRAHAM GOLDBERG, OF NEW YORK, N. Y.

SHIRT

Application filed January 16, 1930. Serial No. 421,215.

This invention relates to wearing apparel, and has particular reference to an improvement in men's shirts.

The popularity of the soft or semi-soft 5 turn down collar, either attached to or detached from the shirt, has led to the necessity of employing some means for connecting together and holding down the points of the collar. Various devices have been employed for this purpose, such as a pin, a clasp, 10 buttons and buttonholes, stiffener elements in the forward edges of the collars and the like. All of these devices have been open to certain objections and possess certain disadvantages, principally due to the visibility 15 of the means employed, which detracts from the appearance, or the fact that some of them, such as buttons, interfere with the laundering of the shirt. It has also been observed that by merely employing connecting 20 devices between the collar points, there is also a tendency for the collar to wrinkle.

The present invention, therefore, primarily aims to provide an extremely simple and 25 inexpensive yet highly effective means for remediating the aforementioned unsatisfactory conditions which prevail, by providing an aperture in the upper portion of the overlapping front edge of the shirt spaced from 30 the free edge and through which may be trained any form of connecting device for the collar points, so that the same is concealed from view by the portion of the front of the shirt which it underlies and whereby said 35 apertured portion of the shirt constitutes means with which the collar point connecting device engages to hold the collar points down for maintaining the collar in a smooth condition.

With the above recited and other objects in view, reference is had to the following description and accompanying drawings, in which there is exhibited one example or embodiment of the invention, while the claims 45 define the actual scope of the same.

In the drawings:

Figure 1 is a fragmentary front view illustrating a shirt constructed in accordance with the invention, with which the collar point connecting means is actively associated.

Figure 2 is a similar view illustrating one point of the collar disconnected from its connecting means and showing the connecting means extending through the aperture in the shirt.

Figure 3 is a fragmentary enlarged horizontal sectional view taken approximately on the line indicated at 3—3 in Figure 1.

Referring to the drawings by characters of reference, A designates a shirt of the conventional type provided with the usual buttonhole strip or pleat B which extends from the collar point downwardly and which is designed to overlap the other front edge of the shirt and receive the buttons C through the buttonholes D thereof. The collar E as illustrated is shown as of the attached type, but, obviously, within the scope of the invention, the same may be of the detached type, and said collar is provided with the usual points F. The connecting device may be of any desired type, but for the purposes of illustration there is illustrated a strip or tape G which is provided at its opposite ends with buttons H which are adapted to be buttoned into buttonholes I on the under side of the collar points F. The particular feature of the present invention resides in the provision of a slot or aperture J which is formed in the bosom of the shirt adjacent the free edge 60 of the overlapping portion of the front and spaced from said free edge an appropriate distance, so that the connecting device G may be threaded through the slot or aperture J to protrude therefrom for connection with one 65 wing or point F of the collar, the opposite end to protrude beyond the free edge of the overlapping portion for connection with the opposite point or wing F of the collar. Obviously, this conceals the connecting device 70 from view under the overlapped portion of the shirt front, while at the same time the connecting device G is anchored to the shirt to hold the collar points F down and maintain 75 the collar in a smooth unwrinkled condition.

As previously explained, the device G may be of any type which establishes a connection between the collar points or wings. It is also apparent that the slot or aperture J may be 80

reinforced at its edges in the form of a buttonhole to prevent fraying of the fabric.

What is claimed is:

1. A shirt of the type which opens in the front, said shirt having an aperture in the bosom spaced from the free edge of the overlapping portion of the front of the shirt adjacent the collar, said aperture constituting means for receiving therethrough a member designed to establish a connection between the points of a collar, the opposite ends of which member project beyond the free edge of the overlapping portion and the apertured portion of the shirt front.
2. The combination with a turn down collar and a member having means at its opposite ends for connecting together the points of the collar, of a shirt of the type which opens at the front and which shirt is formed with an aperture adjacent the free overlapped edge for receiving therethrough said collar point connecting means, to permit of the disposal of said member beneath that portion of the shirt which lies between its opening and said aperture.
3. In combination, a shirt of the type which opens at its front and which has a buttonhole strip at one side of its front opening, said shirt having an aperture in its front spaced from its opening underlying and normally concealed by one edge of the buttonhole strip and a member having means adjacent its opposite ends for engagement with the points of a turned-down collar, said member being disposed through the aperture under the pleat and out through the opening.

Signed at New York, in the county of New York and State of New York, this 15th day of January, A. D. 1930.

ABRAHAM GOLDBERG.
